PORABLE SPOTLIGHT

David M. Morgenstern, Euclid, Ohio, assignor to Nelmor Corporation, Chicago, Ill., a corporation of Illinois

Application February 8, 1951, Serial No. 14,146

Term of patent 7 years

(Cl. D48—20)

To all whom it may concern:

Be it known that I, David M. Morgenstern, a citizen of the United States, residing at Euclid, in the county of Cuyahoga and State of Ohio, have invented a new, original, and ornamental Design for a Portable Spotlight, of which the following is a specification, reference being had to the accompanying drawing, forming part hereof, wherein Fig. 1 is a side elevational view of a portable spotlight showing my new design; Fig. 2 is a front elevational view thereof; Fig. 3 is a cross sectional view through the handle, taken on the line 3—3 of Fig. 1; and Fig. 4 is a rear elevational view of the spotlight on a reduced scale.

I claim:

The ornamental design for a portable spotlight, as shown.

DAVID M. MORGESTERN.
